MERCURY SWITCH

Carl H. Larson, Elkhart, Ind., assignor to The
Adlake Company, a corporation of Illinois

Application October 17, 1934, Serial No. 748,584

4 Claims. (Cl. 200—112)

In mercury switches having a stationary tube or envelope containing electrodes and mercury displaced by an iron armature to close the circuit, there appears to be an electrolytic (or some other) action between the mercury and the iron, particularly on inductive direct current load that makes the mercury become sluggish and apt to cling on to the armature with the result that the pick-up and drop-away values change, and other desirable characteristics of mercury switches are lost.

The bad effects seem to be the result of current flowing through that portion of the armature which is in the mercury.

The principal object of this invention is to prevent the degeneration of the switch, and this is achieved by bringing the electrodes as close together as is consistent with the necessary gap (which varies with the voltage) and otherwise making any circuit through the mercury and armature of high resistance as compared with the short mercury connector between the electrodes.

In the drawing:—

Fig. 1 is a vertical section through a mercury switch embodying the invention and the parts are shown in the position they assume when the magnet is energized and the mercury is forming a connector between the electrodes of the switch; and

Fig. 2 is a view showing the parts in the position they assume when the magnet is de-energized and the mercury level has dropped to open the switch.

But this specific illustration and the corresponding description are used for the purpose of disclosure only, and are not intended to impose limitations on the claims, for it is realized that the gist of the invention can be variously embodied.

An envelope 10, generally of glass and, preferably, low expansion glass—as disclosed in Weintraub No. 1,154,081—has sealed through it at the bottom lead-in wires 11 and 12 of tungsten, molybdenum, tantalum or the like and they are shielded by glass sleeves 13 and 14 up to about the middle length of the envelope. The sleeve 14 is cut away to expose a suitable length of the lead-in wire 12 to form an electrode 15. The sleeve 13 extends on above the electrode 15 a short distance and the lead wire 11 is bent over to form an electrode 16 extending downwardly, but spaced from the electrode 15 a distance depending upon the voltage for which the switch is de-

signed, also other conditions as those skilled in the art will readily recognize.

The gap between the electrodes 15 and 16 is closed by purified mercury 17 when the electromagnet 18 has been energized and drawn down the displacer, which is composed of a cylindrical armature 19 of ferromagnetic material, in this instance, Swedish iron known as Svea, telescoped over the entire cylinder or sleeve 20 of quartz, glass or any other ceramic or non-magnetic material that will not react with the mercury. The armature and the sleeve are held in assembled relation by the friction of helical springs 21 of piano wire (or any other material that will not react on the mercury) which frictionally engage the projecting ends 22 of the glass tube and extend beyond them to afford cushions for the envelope.

In this instance there is shown between the ends of the armature 19 and the springs 21, rings 20 23 having hardened steel guide fingers 24 to run along a wall of the envelope and guide the displacer in its movements. This, however, is a feature claimed in my copending application Serial No. 748,583, filed Oct. 17, 1934.

This particular embodiment is a front contact switch, but those skilled in the art will readily apply the principles to back contact, as well as other forms of switches.

This glass envelope is approximately 110 mm. 30 long, 15 mm. inside diameter and 17 mm. outside diameter. The top of the sleeve 13 is about 60 mm. from the base of the envelope. The other parts are in proportion, the drawing being approximately twice the size.

Fig. 1 shows the parts in approximately the position they assume when the switch is operating on closed circuit, the magnet being energized. By the magnet being de-energized, the displacer rises and the mercury level drops until the parts assume some such position, as shown in Fig. 2. When the magnet is again energized, the reverse operation takes place.

I claim as my invention:—

1. In a mercury switch, a stationary envelope, lead-in wires sealed through the envelope, a charge of mercury within the envelope, a displacer for the mercury including an iron sleeve and a sleeve of insulating material and electrodes connected with the lead-in wires and spaced apart but close together within the insulating sleeve, said insulating sleeve substantially inhibiting the passage of stray current through the iron sleeve.
2. In a mercury switch, a stationary envelope,

- lead-in wires sealed through the envelope, a charge of mercury within the envelope, a displacer for the mercury including a hollow armature lined with a sleeve of insulating material, and electrodes connected with the lead-in wires and spaced apart but close together within the insulating sleeve, said insulating sleeve substantially inhibiting the passage of stray currents through the body of the armature.
- 10 3. In a mercury switch, a switch envelope, a mercury fill, spaced electrodes in the envelope, one of which projects upwardly through the mercury fill and is surrounded by an insulating sleeve to a point above the low mercury level, 15 the other having its contact making portion in close proximity to the corresponding part of the first electrode, a cylindrical iron armature telescoped over the contact making portions of said electrodes, and an insulating liner in the armature for protecting the latter from the deteriorat-

ing effect of the electric arc at the electrodes and for inhibiting stray currents from the iron armature.

4. In a mercury switch of the type which includes an iron armature reciprocable with a 5 switch envelope for shifting the mercury level to change the condition of the circuit between spaced electrodes in the envelope, said electrodes being arranged so as to limit the flow of current through the mercury to a very small portion thereof within the armature whereby the remainder of the mercury can effectively dissipate the heat that is created by the resistance of the mercury, and means for insulating the interior of the armature to prevent stray currents from passing through the armature and thus contaminate the mercury by the deposit of products of electro-chemical reaction between the iron and mercury.
